UNITED STATES PATENT OFFICE

JAMES BRISCOE, OF ASHLAND, KENTUCKY, ASSIGNOR TO THE AMERICAN LAUNDRY MACHINERY COMPANY, OF CINCINNATI, OHIO, A CORPORATION OF OHIO

STARCHING MACHINE

Application filed August 4, 1930. Serial No. 472,793.

My invention relates to starching machines and, particularly, to apparatus for handling clothes during the starching operation.

Heretofore, the starching step which is necessary with some types of clothes being laundered has been a more or less slow and tedious operation due to the fact that the clothes were placed into a vat or container containing a starch solution and then taken out of the solution by hand and the starch expressed from the clothes by wringing. It was particularly a tedious task to locate smaller articles inasmuch as they could not be seen and were found only by feeling around in the solution with the hands. This also gave rise to the possibility of not removing all of the clothes from the solution and also of mixing articles from one load with those of another when operating under an individual bundle system.

In machines of this class, it is highly desirable to permit the excess starch solution to drain from the clothes before they are removed from the container and the starch expressed therefrom by wringing. Also, it is desirable that the operator be able to see the clothes within the container prior to removal thereof, whereby the possibilities of transfer of articles from one bundle to another when operating under an individual bundle method and of loss through leaving articles in the starch solution are eliminated.

In accordance with my invention, these desirable objects and advantages are obtained by providing an outer container for the solution and an inner container that may be wholly or partly perforated to contain the clothes starched, together with suitable means for lifting the inner container a sufficient distance out of the outer container so that its bottom will be above the surface of the starch solution therein while the clothes are being removed therefrom and to permit the excess starch solution to drain from the clothes prior to removal thereof.

Various other objects and advantageous features may be seen in the following description and one embodiment thereof will be seen in the accompanying drawings wherein

similar characters of reference designate corresponding parts, and wherein:

Fig. 1 is a side elevation of a starching machine constructed in accordance with my invention; Fig. 2 is an enlarged vertical cross section of the device shown in Fig. 1; Fig. 3 is a sectional view taken on the line 3—3 of Fig. 1; and Fig. 4 is a view, partly diagrammatic, taken on the line 4—4 of Fig. 2.

Referring to the drawings, I have shown one embodiment of my invention as comprising an outer container 1, preferably circular, suitably supported in a circular frame 2 mounted on spaced pairs of legs 3 and 3' in any well known manner, the top of the container 1, being held in position by a band 4 that is also mounted on the spaced pairs of legs. As shown in Figs. 2 and 3, the container 1 is provided with a bottom 5 that slopes towards a central point, at which point a drain pipe 6 provided with a control valve 7 extends outwardly from the bottom of the container as a means for draining the starch solution therefrom.

As also shown in Figs. 2 and 3, a central or inner container 8 is adapted to fit within the container 1 and is provided with perforations 9 adjacent to and in its bottom. It will be understood that the container 8 may be only partially or may be entirely made up of perforated material.

This inner container is supported on rods 10 adapted to reciprocate within the diametrically opposed pair of legs 3 by means of brackets 11 extending outwardly from the container and secured to the upper ends of the rods 10. The lower ends of these rods rest upon plugs 12 also mounted for reciprocation within the diametrically disposed legs 3 which plugs, in turn, rest upon coil springs 13 whose purpose will be hereinafter apparent. Pivotal pins 14 extend outwardly through slots 15 disposed longitudinally of the legs 3 and the free ends of side bars 16 forming a part of a foot lever arrangement 95 are attached to their respective pins which extend outwardly in axial alignment from the diametrically disposed legs 3. Anti-friction rollers 17 are preferably provided at the point of attachment between the side bars 100

and pivot pins to reduce friction between the operating parts.

The side bars 16 are pivotally mounted intermediate their ends on a rod 17' that is, in turn, supported in brackets 18 depending from the frame 2 and the side bars are so shaped as to straddle or surround one of the supporting legs 3'. A pedal portion 19 is arranged to slide vertically on the one supporting leg 3' by means of a perforation provided therein, the pedal portion being pivotally connected to the side bars 16 by means of links 20 as shown in Figs. 1 and 2. A spring pressed catch 21 is pivotally mounted on the pedal portion 19 in such manner that its nose yieldingly bears against the supporting leg 3' and at a certain point within the length of the supporting leg engages a notch 22.

20 In the operation of this device, a sufficient quantity of starch solution is placed in the container 1 and the container 8 is raised to its uppermost position in which its bottom will be above the starch solution in the container 1 by pushing the pedal portion 19 of the foot lever arrangement hereinbefore described downwardly along the length of the supporting leg 3' which will raise the plugs 12 and rods 10 on which the inner container 8 is mounted. At a given point within the given length of the supporting leg 3' the catch 21 will engage the notch 22 which will hold the container 8 in its raised position as shown in Fig. 2. Then, the articles to be starched 25 are placed in the container 8 and the container permitted to lower by gravity into the starch solution by releasing the catch 21 from the notch 22, any shock exerted by the downwardly moving container 8 being taken up 30 by the buffer springs 13.

40 After the articles have been thoroughly saturated with the starch solution, the container 8 is raised above the starch solution in the container 1 by depressing the pedal portion 19 of the foot lever arrangement hereinbefore described, the catch 21 automatically entering the notch 22 to hold the container 8 in its raised position. With the container 8 in its raised position, the starch solution will 45 drain from the articles in the container 8 whereupon such articles may be removed and any excess or remaining starch solution expressed from the articles in any well known manner. Both the container 1 and 8 may be 50 easily removed from the supporting frame so that the containers may be cleaned as often as is desired.

What I claim is:

1. Apparatus of the character described, 60 comprising an outer container and supporting legs therefor, an inner container movable relative thereto, supporting means for said inner container embodying rods adapted to outer container, and means for moving said 65 reciprocate in the supporting legs of said

rods upwardly within said legs and thereby moving said inner container upwardly within said outer container.

2. Apparatus of the character described, 70 comprising an outer container and supporting legs therefor, an inner container movable relative thereto, supporting means for said inner container embodying rods adapted to reciprocate in the supporting legs of said outer container, and a foot lever arrangement 75 for moving said rods upwardly within said legs and thereby moving said inner container upwardly within said outer container.

3. Apparatus of the character described, 80 comprising an outer container and supporting legs therefor, an inner container movable relative thereto, supporting means for said inner container embodying rods adapted to reciprocate in the supporting legs of said outer container, a foot lever arrangement for moving said rods upwardly within said legs and thereby moving said inner container upwardly within said outer container, and means for maintaining said inner container in its uppermost position. 85

4. Apparatus of the character described, 90 comprising an outer container and supporting legs therefor, an inner container movable relative thereto, supporting means for said inner container embodying rods adapted to reciprocate in the supporting legs of said outer container, means for moving said rods upwardly within said legs and thereby moving said inner container upwardly within said outer container, and means for absorbing 95 shocks as said inner container approaches its lowermost position. 100

In testimony whereof I hereby affix my signature.

JAMES BRISCOE.
